UNITED STATES PATENT OFFICE.

WALTER CLARK SHUMAKER, OF ORANGEVILLE, ILLINOIS.

FACING TOOL.

Application filed November 9, 1921. Serial No. 514,110.

To all whom it may concern:

Be it known that I, WALTER CLARK SHUMAKER, a citizen of the United States of America, and a resident of Orangeville, 5 Stephenson county, Illinois, have invented certain new and useful Improvements in Facing Tools, of which the following is a specification.

My invention relates to improvements in 10 facing-tools, and the object of my improvement is to supply a tool of this class manually operable, and of a convenient and simple design suitable for facing certain bearing-end faces of front axle-yokes and spindle- 15 body bushings such as are used in motor-cars, or for operating on any other devices to which the tool may be applicable.

I have accomplished the above object by 20 the means which are hereinafter described and claimed, and which are illustrated in the accompanying drawings, in which Fig. 1 is an elevation of said tool with an element thereof in partial section, as employed to face the lower bearing-end of the upper 25 member of an axle-yoke and Fig. 2 is another elevation of the tool with its elements rearranged and employed to face the outer end of a spindle-body bushing. Fig. 3 is a 30 plan of one end of the cutter-head of said tool, and Fig. 4 is a plan of a washer used in connection with the tool.

In said drawings, similar numerals of reference denote similar parts throughout the several views.

35 My improved facing-tool comprises but few coacting elements. The numeral 1 denotes a cylindric bolt-shaped shaft having a squared head 2 and having its opposite end exteriorly threaded at 4, and having a 40 key seat 23 throughout the length of the thread on its longitudinal axis. The shaft 1 has a pair of longitudinally spaced cylindric transverse orifices 3 near the head 2.

The numeral 8 denotes a hollow cylindri- 45 cal cutter-head mounted slidingly upon said shaft 1, and has a cylindric transverse pas- 50 sage 15 adapted for alined registration with either of the orifices 3, a headed pin 14 being inserted in either case to secure the cutter- 55 head in an adjusted position on said shaft. The head 8 on one side has an angular groove 9, which, together with a longitudinal and sloping shoulder or abutment 10 furnishes a seat for the oblong cutter-tool 13. Fig. 1 of the drawing shows a cutter head with a

single cutting blade 13, but it is apparent that a cutter head may be used having one or more cutting edges, either integral or detachable. The shoulder 10 as also the tool 13 have alined orifices 11 to receive the se- 60 curing screws 12.

The numeral 5 denotes a body having one end part squared with an end socket 7 in- 65 teriorly threaded, the other end diminished end being exteriorly threaded at 6.

The numeral 16 in Fig. 4 denotes a washer 70 having an integral tongue 24 projecting in- 75 wardly, of suitable width and length to en- gage the key seat 23 at the lower threaded end 4 of the shaft 1. It is understood that 70 the inside diameter of the washer 16 is such that it slides readily on the threaded end 4 of the shaft 1 and is prevented from turn- 80 ing by the engagement of the tongue 24 in the key-way 23.

The tool is particularly well adapted for 85 use in facing work on the yokes and the 90 spindle-body bushings of a well-known type 95 of car, but of course, is not restricted there- 100 to, as it is adaptable to any axle yoke and 105 spindle body of similar design.

In Fig. 1 is shown an end part of a front 110 axle 17 having an integral terminal yoke, 115 vertically spaced and whose fork extremities 120 are cylindrically vertically orificed in aline- 125 ment to receive a spindle-bolt, not shown.

As the shaft 1 of the tool is of like dimen- 130 sions to such a spindle-bolt, it may be passed 135 through said alined orifices as also through 140 the hollow of the cutter-head 8, the latter 145 being then located between the bifurcations 150 of the yoke, with its tool-bit 13 projecting 155 upwardly into contact with the lower bear- 160 ing face 18' of the upper yoke-member 18 165 surrounding the shaft 1. The cutter-head 170 is then secured by means of the pin 14. The 175 lower threaded end 4 of the said shaft 1 is 180 adjustably supported on the bossed extre- 185 mity 6 of the body 5, as the part 6 is 190 meshed with the threads in the lower yoke- 195 bearing. As the upper bearing face 18' men- 200 tioned is that which sustains the wear of 205 use, this is the one which requires facing 210 accurately to be kept smooth and free from 215 irregularities. The tool is operated man- 220 ually by the application of a wrench or 225 handle to its head 2, to rotate it, while the 230 cutter head 8 is forced against the surface to 235 be faced by the pressure on the lower end 240 of the shaft 1, by means of manually turn- 245

ing the body 5, with the extremity 6 located in the threaded end of the lower yoke bearing.

Referring now to said Fig. 2, the numeral 5 19 denotes a spindle-body provided with the usual knuckle-joint and an angularly projecting spindle to receive the hub of a wheel.

The body 19 has a longitudinal hollow or bore 20, and in both ends of said hollow are 10 seated the flanged bushings 21 and 22, of like shape, usually made of brass, and serving as bearings for the spindle-bolt. The outer ends of said bushings are faced by the use of said tool, it being necessary to re- 15 move the cutter-head and reverse it in position

on the shaft 1. In the use of the tool as shown in Fig. 2, the projecting lower threaded end 4 of said shaft 1 has the threaded socket 7 of the body 5 fitted upon it 20

for vertical adjustments as needed in the progress of the work. The tongued washer 16 is interposed upon said shaft 1 between the lower end of the lower bushing 21 or 22 and the bearing end of the body 5 with said 25

tongue 24 in engagement with the key seat 23 on the shaft 1, to insure that socket 7 of the body 5 rotates with the shaft 1 as it is rotated. The tool is operated for facing the 30 spindle body bushings 21 and 22 by rotating

it manually or otherwise, while the cutter head 8 is forced against the bushing face by means of pressure exerted by tightening body 5 on the threaded end 4 of the shaft 1. The tongued washer 6 prevents the body 35

5 from bearing directly against the face of the bushing 21 or 22 and the consequent stoppage of its rotation with the shaft 1, which would result in excessive feed and

gouging of the cutting blade 13 into the bushing face. By means of the tongued 40 washer 16, the body 5 rotates with the shaft 1, and a fine or coarse cut may be taken at will, depending upon how tightly the body 5 is forced against the washer 16. It is apparent that other constructions may be used 45 in place of the tongued washer 16, to bring about the aforesaid results, and it is my purpose not to limit my invention to this single construction, but to cover other means of achieving such a result, as by means of 50 squared or flattened inside edge of washer, or other means, to insure the rotation with the shaft 1.

Having described my invention, what I claim as new and desire to secure by Letters 55 Patent, is:

A facing-tool, comprising a rotatable shaft having one end threaded with a longitudinal key-way in said threaded part, a reversible bit secured removably and longitudinally adjustably upon said shaft, a washer removably and slidingly mounted upon said shaft and having a key-projection extending into said key-seat, and a socket-nut having one end exteriorly threaded, the socket thereof fitting the threaded end of said shaft; the exteriorly threaded end of the socket-nut when reversed being adapted to fit the interiorly-threaded hole of a supporting-body in alinement with and adjustably supporting 60 the abutting end of said shaft to hold the bit thereon in adjusted engagement with the object to be faced.

Signed at Orangeville, Ill., this 5th day of November, 1921.

WALTER CLARK SHUMAKER.
